UNITED STATES PATENT OFFICE.

IVAN E. NELSON, OF SANTA CLARA, CALIFORNIA.

ORE-SEPARATOR.

1,179,744.

Specification of Letters Patent. Patented Apr. 18, 1916.

Application filed November 1, 1911. Serial No. 658,022.

To all whom it may concern:

Be it known that I, IVAN E. NELSON, a citizen of the United States, residing at Santa Clara, in the county of Santa Clara and State of California, have invented certain new and useful Improvements in Ore-Separators, of which the following is a specification.

This invention relates to improvements in ore separators and especially that type known generally as dry washers, or devices in which air is employed to promote the separation.

One of the objects of the invention is to provide a device of this type with a series of screens and riffles and means for collecting the fine gravel and sand to assist the elimination of the gold, by jets of air, or suction pipes creating air jets.

With the above and other objects in view the invention relates to certain combinations, constructions and arrangements of parts, clearly described in the following specification and clearly illustrated in the accompanying drawings in which,

Figure 1 is a side elevation partly broken away of the improved separator. Fig. 2 is a top plan view. Fig. 3 is a detail sectional view of a collecting plate for sand. Fig. 4 is a fragmentary sectional plan view illustrating the vibrating means. Fig. 5 is a detail sectional view on an enlarged scale showing the arrangement of the riffles and a part of the rocking means. Fig. 6 is a detail plan view of the bottom of one of the air section hoods. Fig. 7 is a longitudinal vertical sectional view through a screen, hood and hopper.

Referring to the accompanying drawings illustrating the preferred form of the invention 1 denotes the base of the machine and 2 a suitable ore hopper. The hopper 2 feeds to an elevator belt 3, which is movable over wheels 4, journaled on the frame members 1'. The belt 3 has a plurality of ore buckets which are adapted to deliver ore to a chute 6, which leads to a hopper 7. The hopper 7 is supported over a screen 8, and the screen 8 is supported over a second screen 9, and the screen 9 is supported over a third screen 10, which third screen is supported over a collecting plate 11.

The screen 8 is arranged over a hopper 12, which is adapted to deliver material passed through the screen 8 to the screen 9, which screen 9 is arranged over a hopper 13, which

delivers material passed through the screen 9 to the screen 10, which screen 10 is arranged over a hopper 14, which delivers material passed through the screen 10 to the collecting plate 11.

The hoppers are covered by hoods 15' on which riffle plates 15 are arranged, each riffle plate being provided with an inwardly curved upper edge. The riffles are arranged in steps, as shown in Figs. 1 and 5. Between the riffles on the hoods adjacent the two upper screens mercury is arranged to collect gold in the usual way, while over the hoods adjacent the lower screen and collecting plate suction tubes or pipes 16 are arranged, their inlet ends being provided with hoods 17, which are open at their ends and at their bases and are supported above the hood or plate.

The pipes 16 are connected to the air tank or suction chamber 18 which communicates by a pipe 19 with the interior of the suction casing fan 20, which is operated by a suitable belt or other means. The tank 18 is provided with a suitable delivery point or end, whereby the sand can be taken from the tank.

A vibrator shaft 22 is journaled at its ends to the frame 1 and is driven by a belt 21. Brackets 23 hold the shaft 22 rigidly on the frame 1. Eccentrics 24 are mounted on the shaft 22 and eccentric straps 24' are arranged on said eccentrics and are connected by means of the rods 24'' with the yokes 29^a, the terminals of which connect with vertical arms or rods 29^b which are secured to the frame 29 for supporting the screens and plate 11. The frame 29 is connected to parallel angle bars 28. Horizontal supports 25 are arranged on the frame 1 and angular rods 27 are secured to said supports, and on the upper free ends of said rods rollers 26 are arranged. These rollers 26 are adapted to normally bear against the outer surfaces of the angular bars 28 carried by the screen frames 29. When the shaft 22 is rotated the eccentrics will impart a vibratory movement to the screens and plate 11 and the rollers 26 will transform this movement from a normally circular like orbit to a more irregular one, whereby the ore will be more effectively agitated.

The ore falling from the hopper 7 will be separated partly by the screen 8, the larger stones passing over the screen and falling into the spaces between the riffles, thus per-

mitting the mercury to come in contact therewith, the ore passing through the screen will be again subjected to the separating action of another screen, with a finer 5 mesh, and the ore passing through the second lower screen will be subjected to the separating action of the third lower screen 10, and the ore passing through the still finer openings of this screen will fall upon the 10 collecting plate 11, designed principally to collect sand. The material falling into the spaces between the riffles on the screen plate 10 and on the collecting plate 11 will be drawn into the tank 18 by the pipes 17, the 15 terminals of which are disposed on different planes and which are of different lengths, as shown in Figs. 1 and 2. In this way the use of water is dispensed with.

Having described my invention I claim:

- 20 1. In an ore separator, a supporting member, a screen carried thereby and riffles in series disposed on the same around said screen and suction tubes arranged over said riffles.
- 25 2. In an ore separator, a supporting member, a screen carried by the same, and riffles around said screen, said riffles having inwardly curved upper edges and arranged in steps and suction tubes arranged over said 30 riffles.
3. In an ore separator, a supporting member, a screen carried by the same, riffles around said screen and hoppers provided with hoods on which said riffles are arranged, and suction tubes supported above 35 said screen.
4. In an ore separator, a supporting member, a screen carried by the same, riffles around said screen and hoppers provided 40 with hoods on which said riffles are arranged, and suction tubes provided with

hoods at their inlet ends and supported above said screen.

5. In an ore separator, a series of screens, a series of hoppers thereover, hoods for said 45 hoppers, and riffle plates arranged around the hoods and supported by said hoods, said riffle plates being arranged in steps and each provided with an inwardly curved upper edge and suction tubes over the hoods and 50 adjacent the riffles.

6. In an ore separator, a series of screens, a series of hoppers thereover, hoods for said hoppers, and riffle plates arranged around the same, each riffle plate being provided 55 with an inwardly curved upper edge, suction tubes over said hoods and provided with hoods at their inlet ends.

7. In an ore separator, a series of screens, a series of hoppers thereover, hoods for said 60 hoppers, and riffle plates arranged around the same, each riffle plate being provided with an inwardly curved upper edge, said riffle plates being arranged in steps, suction tubes over said hoods and provided with 65 hoods at their inlet ends.

8. In an ore separator, a hopper, a screen arranged over the same, a hood for said hopper, riffle plates arranged on said hood, each riffle plate having an inwardly curved 70 upper edge, said riffles being arranged in steps, a series of suction tubes over said hood adjacent the screen, and hoods for the inlet ends of said tubes, said hoods being open at their ends and bases and supported above 75 the riffles.

In testimony whereof I affix my signature in presence of two witnesses.

IVAN E. NELSON.
